(57) **CLAIM**

The ornamental design for a yarn holder apparatus, as shown and described.

DESCRIPTION

FIG. 1 is a front perspective view of the yarn holder apparatus according to the present design;

FIG. 2 is a front view of the yarn holder apparatus seen in FIG. 1.

FIG. 3 is a back view of the yarn holder apparatus seen in FIG. 1.

FIG. 4 is a right side view of the yarn holder apparatus seen in FIG. 1.

FIG. 5 is a left side view of the yarn holder apparatus seen in FIG. 1.

FIG. 6 is a top view of the yarn holder apparatus seen in FIG. 1; and,

FIG. 7 is a bottom view of the yarn holder apparatus seen in FIG. 1.

The broken lines depict portions of the article that form no part of the claimed design.

1 Claim, 7 Drawing Sheets
